UNITED STATES PATENT OFFICE.

UICHIRO MAEDA, OF LOS ANGELES, CALIFORNIA.

SKIRT-TEMPLLET.

1,390,534.

Specification of Letters Patent. Patented Sept. 13, 1921.

Application filed August 16, 1919. Serial No. 318,017.

To all whom it may concern:

Be it known that I, UICHIRO MAEDA, a citizen of Japan, residing at Los Angeles, in the county of Los Angeles and State of California, have invented new and useful Improvements in Skirt-Templlets, of which the following is a specification.

This invention relates to skirt templlets, and is particularly adapted to be used as a guide for the cutting out of ladies' and children's dress skirt patterns to conform to any desired measurements.

The object of my invention is to provide a templlet whereby anyone, even though they be unskilled in the art, may cut a skirt pattern with accuracy, and in proper proportions, in accordance with given measurements.

Other objects will appear in the following description, will be pointed out in the claim, and embodied in the accompanying drawings, in which:

Figure 1 is a plan view of my invention, drawn on a small scale, no attempt being made as to the accuracy of the division marks.

Fig. 2 is an edge view of the same.

Fig. 3 is a plan view of a sheet of paper showing a pattern of half of the front of the skirt, and half of the back of the skirt, laid out on the same by the use of the templlet.

Fig. 4 is a plan view of the front half of the skirt pattern after it has been cut out from the paper, shown laid in proper position upon a piece of cloth after said cloth has been folded at the front edge of the pattern.

Fig. 5 is a transverse section taken on the line 5—5 of Fig. 1.

Fig. 6 is a transverse section taken on the line 6—6 of Fig. 1.

Fig. 7 is a transverse section taken on the line 7—7 of Fig. 4.

Fig. 8 is an enlarged view of the top portion of the templlet showing the divisional marks more accurately.

In carrying out my invention I employ a body portion 10, preferably composed of a thin sheet of leatherboard, cardboard, or metal, which is shaped to conform to the half of a large skirt, extending from the front to the back. The edge 11 represents the front of the skirt, 12 the back, 13 the waist line, and 14 the bottom. The body

portion 10 is preferably made in two sections 15 and 16 secured together by a plurality of common snap fasteners 17, in order that the templlet may be readily taken apart and the two sections placed side by side for convenience in transportation.

The body portion 10, just below the waist line 13, and in parallel relation therewith, is provided with two groups of perforations 18 and 19, which represent the true waist line of the skirt. The perforations 18 are spaced apart in quarter inch spaces, starting three and one-half inches from the perforation A adjacent the front of the templlet and continuing inwardly for a suitable distance, 70 and all but the first four perforations being numbered from 18 to 37, as shown, with the zero point at A. Ending with a point B at the back of the skirt is a similar set of perforations 19, which are in alinement with 75 the perforations 18, and are arranged in quarter inch spaces, the alternate perforations being numbered from 45 at B to 26 or 27.

Arranged a suitable distance below the 80 perforations 18 and 19, are two groups of perforations 20 and 21, which represent the hip line, extending between perforations C and D arranged respectively adjacent the front and back edges of the templlet, the total 85 distance between said points representing forty-five inches. The perforations of group 21 are spaced at half inch intervals from 45 at the back of the skirt, inwardly to 26 or 27, the ending point D being arranged directly below the point B. The perforations of group 20 are spaced at quarter inch intervals and are numbered up to 45 at E, on the scale 1 of which C is zero, which brings the point E midway between 90 the points C and D.

A group of perforations 22 are arranged along the front edge of the templlet 10, and are adapted to determine the front length of the skirt, and are spaced at one inch intervals starting from a point twenty-three inches below point A and running downwardly, each perforation being numbered in accordance with its distance in inches from point A. Another group of perforations 23 are arranged at one inch intervals parallel to the back edge of the templlet directly in line with the points B and D and numbered in accordance with their distance from B in inches. Each perforation in this verti- 100 105 110

cal group is the final perforation of a group, the members of which are spaced at inch intervals and are numbered inwardly from a maximum of 45 to a minimum of 27. 5 Still another group of perforations 24 are arranged in the templet 10, representing the greatest length of the skirt from the waist line to its bottom. These perforations are spaced one inch apart and are suitably numbered as shown, and enable the operator to 10 determine the proper curvature of the skirt at its bottom.

The templet 10 is provided with a slot 26, arranged just below the groups of perforations 18 and 19 and parallel therewith, and adapted to slide in said slot is the measure 28, which is secured to the male member of a snap fastener 29, the shank of which engages in said slot, as clearly shown in 15 Fig. 5 of the drawings. The measure 28 is provided with a straight edge 30 and a curved edge 31, the purpose of which will be hereinafter explained. The edge 30 of the measure 28 is provided with a series of 20 graduation marks 32 spaced one quarter of an inch apart and numbered in accordance with their distance from the end F beginning with the numeral 18 or 19.

It will be observed that some of the lower 30 numerals for the graduation of the various groups of perforations have been left off, as these are unnecessary for the reason that very small skirts would seldom be cut out with this templet, but it is obvious that all 35 of the perforations may be added if desired, and that all of the groups of perforations may be subdivided in order to obtain measurements in fractions of an inch.

In operating my invention, the templet 40 10 is first laid flat upon a suitable sheet of paper, the measurements of the skirt desired to be cut having first been ascertained. Assuming that it is desired to cut a skirt pattern having the following 45 dimensions: waist twenty-nine inches; hips forty-one inches; front length thirty-three inches and back length thirty-four inches. Pencil marks are made on the paper through the perforations at A, C, G, H, which is 50 directly below perforation L and determines the width of the skirt at its bottom, J, K, and L, the end F of the measure 28 is then placed at L, which indicates forty-one inches hip measurement, and then a pencil 55 mark is made at M, which indicates the point of the dart at the hip just midway between C and J, a pencil mark is then made at N, which represents the waist measurement of twenty-nine inches, and another 60 pencil mark is also made at O which is the point opposite the graduation 29 on the measure 28. These marks at N and O represent the base of the dart at the waist line.

The templet 10 is then moved down on 65 the paper and the upper edge of the same

is used to draw a line through points A and N, and O and L, as shown in Fig. 3 of the drawings. The front edge of the templet is used to draw a line through points A, C and G, the bottom of the templet is 70 used to draw a line through points G, K and H, and the back edge of the templet is used to draw a line through points L, J and H. The measure 28 is then removed from the snap button 27 and the curved edge 31 of 75 the same is used to draw lines through M and O, and M and N. The distance between points G and H on the pattern is then equally divided establishing a point P, and a line is then drawn between points M and P. 80

After the pattern has been laid out on the paper as above described, the paper is cut on the line established, thus providing patterns for half of the front of the skirt and half of the back of the skirt. These patterns are 85 then laid on a piece of dress goods which has been folded, as shown in Figs. 4 and 7, said figures representing only the front half of the pattern, the back half being handled in a similar manner. 90

It is obvious that the pattern cut by the use of my templet provides all of the basic measurements necessary to the cutting out of a perfectly fitting skirt, and that the ingenuity of the maker may be brought into 95 play in allowing for the seams, and for ornamental embellishments.

It is also to be observed that by the use of my templet that the point of the dart at M of the hip line will always be midway between the front and back of the skirt and that the distances between A and N, and O and B will always be equal and just one quarter of the waist measurement, regardless of the relative measurements of the 105 skirt desired to be cut.

What I claim is:

A templet adapted to be used for the laying out of a skirt pattern to correspond to predetermined measurements, said templet being provided with a plurality of measurement indicating points at the waist, hip, front and back lines of a skirt, said indicating points at the waist and hip lines extending approximately across the templet 110 between its front and back edges and representing measurement units, said templet being further provided with indicating points for establishing the point of the dart of the skirt on said pattern midway of predetermined measurements at the hip line and for establishing the points of the flare of 115 said dart at predetermined distances from the front and back edges of the skirt pattern. 120

In witness that I claim the foregoing I have hereunto subscribed by name this 30th day of July, 1919.

UICHIRO MAEDA,
